UNITED STATES PATENT OFFICE.

FREDERIC R. BARKER, OF BROOKLINE, MASSACHUSETTS.

INTERNAL-COMBUSTION ENGINE.

1,111,051.

Specification of Letters Patent. Patented Sept. 22, 1914.

Application filed June 25, 1913. Serial No. 775,323.

To all whom it may concern:

Be it known that I, FREDERIC R. BARKER, a subject of the King of Great Britain, residing at Brookline, in the county of Norfolk and State of Massachusetts, have invented new and useful Improvements in Internal-Combustion Engines, of which the following is a specification.

This invention relates to new and useful improvements in internal combustion engines particularly of the four cycle type. In this type of engine an explosion occurs in each of the cylinders thereof for every two complete rotations of the crank shaft or for every four complete movements of the piston and by reason of the time which elapses between the successive explosions, a large heavy fly-wheel must either be employed to carry the load from one explosion to the next or said engine must be operated at a very high rate of speed, or there is still another method of overcoming this difficulty and that is by providing a plurality of cylinders thus insuring substantially a uniform application of energy to the crank shaft. The latter method seems to have the preference especially in automobile engines, but this method results in a substantial increase in the cost of manufacturing the engine owing to the large number of duplicate parts required.

The object of the present invention is to provide an engine embracing the advantages of the latter construction, but in a simplified and consequently less expensive manner, and consists in providing a plurality of sets of cylinders one of the cylinders of each set being arranged substantially concentric with the other cylinder of that set and a single piston having bearing members adapted to engage both of the cylinders in its respective set.

The invention further consists in providing a single valve for opening and closing both the inlet and exhaust ports for both of the cylinders in each set to control the admission of the combustible charge to both of said cylinders and the discharge of the burnt gases therefrom.

The invention still further consists in providing instrumentalities for simultaneously rotating and reciprocating said valves to control said gases.

The invention finally consists in the combination and arrangement of parts as set forth in the following specification and particularly pointed out in the claims.

Referring to the drawings: Figure 1 is a longitudinal sectional elevation of an engine embodying my invention. Fig. 2 is a transverse section partly in elevation taken on line 2-2 of Fig. 1 and looking in the direction of the arrows on said line. Fig. 3 is a plan view of the top of the engine. Fig. 4 is a section taken on the irregular line 4-4 of Fig. 1, illustrating the arrangement of the gearing for rotating the cylindrical sleeve valves. Fig. 5 is a section taken substantially on the irregular line 5-5 of Fig. 1, illustrating the arrangement of the various inlet and exhaust passages and pipes for the upper cylinders. In this figure the entire passages 43 and the interior of the manifold 46 are shown in full lines in the right-hand end of said figure to more clearly illustrate the same, although the section line does not drop as low as the center of said passages 43 in Fig. 1. Fig. 6 is a section taken substantially on the line 6-6 of Fig. 1 showing the several inlet and exhaust passages for the lower cylinders, parts of said device being broken away to save space. This figure is also somewhat distorted to clearly illustrate the connections between the lower branch 44 of the passage 43 and the manifold 46 and also illustrating the connection between the passage 60 and the exhaust manifold 61. Fig. 7 is a detail sectional elevation taken on line 7-7 of Fig. 6 illustrating portions of the valve operating mechanism and pumps. Fig. 8 is a transverse sectional elevation taken on the irregular line 8-8 of Fig. 1. Fig. 9 is a detail section taken on line 9-9 of Fig. 3. Fig. 10 is a detail side elevation of the gear for imparting a rotary motion to the valve sleeve. Fig. 11 is a development of the valve reciprocating cam. Fig. 12 is a development of a portion of one of the larger cylinders illustrating the inlet and exhaust ports therefor. Fig. 13 is a development of the valve sleeve illustrating the relative positions of the inlet and exhaust ports for both the larger and smaller cylinders. Fig. 14 is a development of a portion of one of the smaller cylinders showing the arrangement of the inlet and exhaust ports therefor.

Like numerals refer to like parts throughout the several views of the drawings.

In the drawings, 18 is an engine casing provided with a plurality of parallelly arranged cylindrical chambers 19 arranged in a row and opening into a chamber 22 which constitutes a crank shaft chamber within

which a crank shaft 23 is journaled to rotate in bearings 24, 25, 26 and 27. The chambers 19 are all substantially alike in construction and extend upwardly through said casing to 5 the top thereof and preferably terminate in annular recesses 28, said recesses being arranged concentric with said chambers. The upper ends of the annular recesses 28 are each separately closed by a cylinder head 31 10 which is secured to the casing 18 preferably by bolts 34. This head is provided with a depending stem 35 which protrudes into the cylinder 19 and is concentrically arranged relatively thereto and constitutes a liner 15 therefor, said stem having a cylindrical chamber 38 substantially smaller in diameter than the chamber 19 and coaxially arranged relatively thereto. Each of said liners or stems is provided with oppositely disposed 20 inlet ports 41, 41 adjacent the upper ends of the chambers 38 and these inlet ports register in turn with the upper ends or branches 42 of inlet passages 43 which are formed in the casing 18 outside of the chambers 19, 25 whereby the combustible mixture may be conducted into said chambers 38 which constitute explosion chambers. The inlet passages 43 are also provided with lower ends or branches 44 which are adapted to conduct 30 portions of said combustible mixture to the lower portions 45 of the chambers 19 through slots 48, said portions 45 constituting the large explosion chambers. A piston 49 is arranged in each of the several sections of 35 said casing and embodies in its construction a bearing member 50 arranged adjacent the upper end thereof and engages the walls of said smaller cylinder 38, while a larger bearing member 51 arranged adjacent to the 40 lower end of said piston engages the walls of the larger cylinder 45, said larger bearing member forming an annular shoulder 52 against which the force of the explosions occurring in the cylinder 45 will be directed. 45 The pistons 49 are provided with the usual wrist pins 53 which are connected by means of connecting rods 54 to crank pins 55 formed on the crank shaft 23 and arranged preferably 120° apart, as illustrated in Fig. 50 1. By this construction it will be seen that each piston performs the function of two pistons of the ordinary type of engine and in the present arrangement where three sets of cylinders are shown the results accomplished will be the same as though six cylinders and six pistons were employed. By arranging said cylinders in sets one within 55 or substantially concentric with the other and near enough to permit the bearing members of the piston to be formed integral one with the other the expense of construction will be greatly reduced owing to the number of parts eliminated and the reduction in size and length of the crank shaft and in the dimensions of the engine in general.

The combustible mixture is delivered to the inlet passages 43 through a manifold 46, said manifold being connected to the casing 18 of the engine in any suitable manner with its outlet openings 47 alining with the openings for the several inlet passages 43 respectively, while a single supply pipe 56 conducts the mixture from the carburetor, not shown in the drawings, to said manifold.

In addition to the oppositely disposed inlet ports for the sets of cylinders the cylinders 38 are provided with oppositely disposed exhaust ports 57 which aline with exhaust passages 58 in the casing 18, while the cylinders 45 are provided with exhaust 80 ports 59, said passages 58 and ports 59 being united or connected by passages 60. Each of the sets of cylinders are provided with these passages and each of said passages 60 are connected with an exhaust manifold 61.

At the proper times in the operation of the engine the combustible mixture is admitted to each of the sets of cylinders, which constitute the chambers 38 and 45, by suitable instrumentalities which admit said mixture first to one of said chambers and then to the other. Furthermore said instrumentalities are adapted to permit the passage of the burnt gases from said cylinders subsequently to the explosions of said combustible mixtures in said cylinders. These instrumentalities include a cylindrical sleeve valve 62 provided with exhaust openings 63 which are adapted to be moved into alinement with the ports 57 and 58, and inlet openings 64 and 65 adapted to be moved to aline with the ports 41 and slots 48 respectively of the cylinders 38 and 45. The exhaust ports 59 for the lower or larger cylinders 45 are controlled by the lower edge 66 of said sleeve. To open and close the various ports a continuously rotating reciprocal movement is imparted to said sleeve, this compound movement being accomplished by means preferably including a sleeve 67 arranged in the annular recess 28 surrounding said valve 62 and engaging a hardened steel ring 68 at the bottom of said recess and another steel ring 69 arranged adjacent the upper end of said recess against the inner face of the cylinder head 31, said sleeve having an annular gear 70 formed thereon by means of which a rotary motion may be imparted to said sleeve. This sleeve is further provided with oppositely disposed longitudinal slots 71 which extend for a portion of the length of said sleeve and receive studs 72 mounted upon the exterior surface of the valve 62 and by means of which a rotary motion is transmitted from said sleeve to said valve. The valve 62 is further provided with rolls 73 pivotally mounted adjacent to said studs 72 upon the interior surface of said valve 62, said rolls 73 engaging a serpentine cam 74 arranged upon the outer face 130

of the stem 35. Said cam and said rolls constitute means which are rendered effective by the rotary movement of said valves 62 whereby a reciprocatory movement may be imparted to said valve.

As hereinbefore stated each of the sets of cylinders is a duplicate of the other of said sets and all of them are provided with valves, as hereinbefore described, which are rotated or operated by the annular gears 70. To simplify the construction of the engine and reduce the expense these gears 70 are geared together preferably by intermediate gears 75 mounted in recesses 76 formed in the casing 18 and upon studs 77, consequently upon transmitting a rotary motion to any one of said valves the other valves operatively connected thereto will simultaneously be rotated. The initial power for rotating said valves is preferably transmitted from the crank shaft of the engine by means preferably consisting of a spiral gear 78 fast to the crank shaft 23 which engages a second spiral gear 79 mounted upon a shaft 80 which, for reasons hereinafter set forth, is journaled in bearings 81 at the righthand end of the engine, see Figs. 1, 6 and 7. A gear 82 is secured to said shaft 80 and engages a gear 83 secured to a shaft 84 journaled in bearings 85 and 86 on the casing 18. A gear 87 is also secured to said shaft 84 at the upper end thereof and is operatively connected to the gear 70 of the adjacent set of cylinders by means of an intermediate gear 88, thereby operatively connecting said last mentioned gear 70 with the crank shaft of the engine, but by reason of the differences in the sizes of the gears 88 and 87, 88 and 82 and 79 and 78 respectively the speed of said sleeve valve relatively to that of said crank shaft will be greatly reduced.

By the above arrangement an indefinite number of cylinders may be provided in a row and the valves therefor all operated by said engine driven instrumentalities. Furthermore if desired another section similar to the section illustrated in Fig. 1, but without the shaft 84 and the shaft 80, may be arranged adjacent the righthand end of the engine illustrated in Fig. 1 with the squared end 89 of its crank shaft projecting into the correspondingly shaped hole 90 of the spiral gear 78 and an intermediate gear similar to 88 provided intermediate the gear 87 and the gear 70 of the first or adjacent valve in said other section, thus operating twice as many valves, with the same instrumentalities, than are shown in the drawings and increasing the power of the engine without doubling the expense or materially increasing the cost thereof.

The cylinders 38 and 45 are provided with independent water jackets 91 and 92 respectively. The water jackets 91 are formed

by recessing the stems 35 to permit water to be circulated substantially to the bottom thereof, the chambers constituting said jackets having ports 93 and 94 arranged adjacent the upper faces of the cylinder heads 31.

The chambers constituting the jackets 92 surround the cylinders 45. Said chambers extend upwardly through the casing 18 around the various inlet and exhaust passages for the several cylinders, whereby the combustible charge which is being conducted through the several inlet passages and ports may be heated to a certain degree while the temperature of the exhaust charges or burnt gases may be partially lowered. These chambers are likewise provided with ports 95 in the upper face of the casing 18 adjacent said cylinder heads, said ports forming the terminals for passages 96 which extend downwardly at one side of each of the chambers 19 to the chamber constituting said water jacket and said ports are connected by means of a pipe 97 with the ports 92 arranged upon the same side of a vertical plane containing the median axial line of the crank shaft of said engine. Said pipe permits water to pass from the water jackets 92 into the water jackets 91 from whence it is discharged through the ports 93 which are arranged upon the opposite side of said vertical plane, and into a pipe 98 which conducts said water to a suitable radiator, not shown in the drawings, or discharges the same if desired. An inlet port 99 through which the water is supplied to said water jackets is arranged adjacent the lower end of one of the water jackets 92, preferably adjacent to the end of the engine at which the gears 82 and 83 are located and communicates with the interior of a casing 100 which surrounds the gears 82 and 83. Said casing 100 is also provided with an inlet 101 upon the opposite side of said gears from the port 99 and as said gears are rotated the teeth thereof create a suction whereby water may be drawn into said casing through said inlet 101 and discharged through the port 99 into the water jackets 92 and around the cylinders 45, thence upwardly through the passages 96, thence through the pipe 97 to the water jackets 91 and from whence said water is discharged through the ports 93 into the pipe 98, said gears 82 and 83 thereby performing a twofold function.

Suitable spark plugs 102 are provided for the cylinders 28, said plugs being arranged in the cylinder heads thereof, the larger cylinders 45 being provided with a pair of oppositely disposed spark plugs 103.

The general operation of the engine hereinbefore specifically described is as follows: Assuming the pistons and valves to be in the positions illustrated in Figs. 1, 2, 4, 5, and 8 and the cylinders represented by the

letters A, B, C, D, E and F, the engine is started in the usual manner and moves the several pistons 49 and the valves 62 to draw in the charges of combustible gases through the inlets 41 and slots 48 and the ports in the valves adapted to aline therewith, while the burnt gases subsequent to the explosions are discharged through the exhaust passages 57, 58 and 59. By reference to Fig. 1 it will be seen that the piston 49 in the cylinder A is on its downward movement, a charge having just been fired in said cylinder, the crank pin for said piston in this case being two-thirds of a rotation down. The piston in the chamber B is at its highest point, the crank therefor being 120° behind the crank pin for the cylinder A. In this cylinder B the charge has just been compressed and about to be fired which will give an added impulse to the crank shaft before the piston in the cylinder A has arrived at its lowermost point and consequently before the charge in said cylinder has been completely spent. In the cylinder C the piston is on its way up to compress a charge which has been previously taken in, the crank operating said piston being 120° behind the crank pin for the piston in the cylinder B. The conditions of said several cylinders just mentioned will all be indicated by the sleeve valves 62 which show that each of said cylinders at this time are closed.

It is the object of the invention to provide an explosion for every rotation of each of the several cranks, thus insuring a substantially uniform application of energy to the crank shaft. To accomplish this the three lower cylinders A, B, and C are fired, as just described, one after another and 120° apart but before the piston in the chamber C is fired said piston must be moved up 120° to compress the charge which has been previously drawn thereinto. During the rotation of the crank shaft through said 120° the piston in the cylinder D will have completed its suction stroke which by the positions of the ports 41 and openings 64 will be seen to be under way and as the explosion occurs in said cylinder C the piston for said cylinder D will start to compress the charge therein and this charge will be fired as the exploded charge in the cylinder C has about completed its expansion. During the firing of the charge in the cylinder D the charge in cylinder E is being compressed while in the cylinder F the suction of the new charge will have just been completed. Thus it will be seen that when one cylinder is compressing another cylinder is discharging.

To accomplish the proper opening of the ports for the several cylinders, the sleeve valves 62 are operatively connected to the crank shaft 23 by the shafts 80 and 84 and the gears thereon to rotate said sleeves one-

half a turn for each two rotations of said crank shaft, while the cam 74 is arranged to elevate said valves twice during each complete rotation thereof. By reason of the above speed ratio the openings in the sleeve valves for the cylinders A, B, C, D, E and R respectively are arranged $\frac{1}{2}$ of a rotation apart, this being equivalent to a movement of the crank shaft 120° , thus causing said openings to register with their proper ports in order to fire the charges and discharge the burnt gas in said several cylinders in the order hereinbefore described.

During the operation of the engine as described the gears 82 and 83 are constantly circulating the water through the water jackets 91 and 92 around the various inlet passages and out through the pipe 98 to a suitable cooling device. By the close proximity of the passages of said water jacket to said exhaust passages and said inlet passages more or less of the heat contained in said exhaust gases will be absorbed by said water and in turn the heat of the inlet passages will be somewhat increased and the charge heated before it is delivered to the cylinders, consequently increasing the efficiency thereof.

From the foregoing description it will be seen that simple and efficient means are provided for accomplishing the objects of the invention, but while the elements herein shown and described are well adapted to perform the functions set forth, it is obvious that various minor changes may be made in the proportions, shape and arrangement of the several parts and in the number of cylinders shown without departing from the spirit and scope of the invention as defined in the appended claims.

Having thus described my invention, what I claim and desire by Letters Patent to secure is:

1. An internal combustion engine embodying, in its construction, a cylinder provided with inlet and exhaust ports, a piston arranged in said cylinder, a rotating reciprocating valve adapted to open and close said ports, rolls mounted on said valve, rotating means for said valve including a sleeve surrounding said valve and provided with longitudinal slots adapted to receive said rolls and permit a longitudinal movement of said valve relatively to said sleeve, means to rotate said sleeve, a cam, and rolls on said valve adapted to engage said cam to reciprocate said valve during the rotary movements imparted thereto by said sleeve.

2. An internal combustion engine embodying, in its construction, a cylinder provided with inlet and exhaust ports, a piston arranged in said cylinder, a rotating reciprocating valve adapted to open and close said ports, a gear surrounding said valve and operatively connected thereto, means to ro-

tate said gear, and instrumentalities rendered effective by the rotation of said gear adapted to impart a combined rotating reciprocating movement to said valve to open 5 and close said ports.

3. An internal combustion engine embodying, in its construction, a plurality of parallelly arranged cylinders provided with inlet and exhaust ports, a piston arranged in 10 each of said cylinders, a cylindrical valve for each of said cylinders adapted to be operated to open and close said ports, engine driven means adapted to rotate one of said valves, means to rotatably connect the other of said 15 valves to said driven valve, and means rendered effective by the rotation of each of said valves adapted to impart a reciprocatory movement to said valves respectively.

4. An internal combustion engine embodying, in its construction, a casing having a cylindrical chamber, a portion of which constitutes an explosion cylinder provided with inlet and exhaust ports, said casing also having an annular recess formed therein 25 concentric with said cylindrical chamber, a rotary member arranged in said recess and provided with oppositely disposed longitudinal slots, means to rotate said member, a cylindrical valve arranged in said cylindrical chamber provided with openings adapted to align with said inlet and exhaust ports, means on said valve adapted to engage said rotary member within said longitudinal slots, a cylinder head adapted to 30 close the end of said cylinder and said annular recess, said cylinder head having a depending cylindrical member provided with a cylindrical chamber constituting an explosion cylinder having inlet and exhaust 35 ports, a cylindrical valve arranged in said first named cylindrical chamber surrounding and adapted to fit said depending cylindrical member, said valve having openings adapted to register with the ports for 40 said explosion cylinders respectively, a stationary serpentine cam on said depending member, means to rotate said valve, means on said valve adapted to engage said cam to reciprocate said valve during the rotary 45 movements thereof, and a piston having bearing members adapted to engage said cylinders respectively and receive explosion 50 impulses therefrom.

5. An internal combustion engine embodying, in its construction, a plurality of sets of parallelly arranged cylinders arranged in a row and in close proximity to each other, each of said sets including a pair of co-axially arranged cylinders, one

of which is smaller than the other, each 60 of said cylinders having oppositely disposed inlet ports and oppositely disposed exhaust ports, a piston for each of said sets of cylinders, said pistons having bearing members for said large and smaller cylinders respectively, 65 a sleeve valve interposed between the large and smaller cylinders of each of said sets, said valves having openings adapted to register with said inlet ports, and instrumentalities adapted to impart a rotating reciprocatory movement to said valves to open 70 and close said ports.

6. An internal combustion engine embodying, in its construction, a plurality of sets of parallelly arranged cylinders arranged in a row and in close proximity to each other, each of said sets including a pair of co-axially arranged cylinders, one of 75 which is smaller than the other, each of said cylinders having oppositely disposed inlet ports and oppositely disposed exhaust ports, a piston for each of said sets of cylinders, said pistons having bearing members for said large and smaller cylinders respectively, a sleeve valve interposed between the large 80 and smaller cylinders of each of said sets, said valves having openings adapted to register with said inlet ports, and instrumentalities adapted to simultaneously 85 impart a rotating reciprocatory movement to said valves to open and close said ports.

7. An internal combustion engine embodying, in its construction, a plurality of sets of parallelly arranged cylinders arranged in a row and in close proximity 95 to each other, each of said sets including a pair of co-axially arranged cylinders, one of which is smaller than the other, each of said cylinders having oppositely disposed inlet ports and oppositely 100 disposed exhaust ports, a piston for each of said sets of cylinders, said pistons having bearing members for said large and smaller cylinders respectively, a sleeve valve interposed between the large and smaller cylinders of each of said sets, 105 said valves having openings adapted to register with said ports, and instrumentalities adapted to impart a rotating reciprocatory movement to said valves to open and close said ports. 110

In testimony whereof I have hereunto set my hand in presence of two subscribing witnesses.

FREDERIC R. BARKER.
